UNITED STATES PATENT OFFICE.

JOHN C. NICHOLS, OF SHEBOYGAN, WISCONSIN, ASSIGNOR TO JOHN C. NICHOLS HARNESS MFG. COMPANY, OF SHEBOYGAN, WISCONSIN, A CORPORATION OF WISCONSIN.

HORSE-COLLAR PAD.

1,258,435.

Specification of Letters Patent.

Patented Mar. 5, 1918.

Application filed May 16, 1917. Serial No. 169,010.

To all whom it may concern:

Be it known that I, JOHN C. NICHOLS, a citizen of the United States, residing at Sheboygan, in the county of Sheboygan and 5 State of Wisconsin, have invented new and useful Improvements in Horse-Collar Pads, of which the following is a specification.

The present invention has reference to horse collars generally, and is more particularly directed to that class thereunder known as neck pads, wherein provision is 10 made for connecting the flexible neck bands therewith in a simple and expeditious manner, consequently adapting the collar to fit 15 various sized necks.

To this end, the invention among other features contemplates the use of a novel construction of buckle so positioned with respect to the retaining plate of the neck pad 20 and connected thereto to not only facilitate in retaining the neck of the collar in a closed position, but serving also as a locking means for the neck, consequently preventing any 25 accidental disconnection of the neck band from the neck pad when the collar is subjected to any undue strains.

With the above and other objects in view, the invention consists in the novel features, 30 details of construction and combination of parts which will hereinafter be more fully set forth, illustrated in the accompanying drawing and pointed out in the appended claims.

Figure 1 is a perspective view of a horse 35 collar illustrating the closed position thereof;

Fig. 2 is a section taken on line 2-2 of Fig. 1;

Fig. 3 is a perspective view of the pad removed from the collar;

Fig. 4 is a perspective view of the upper portion of the collar with a portion of the neck band flaps shown in section, and illustrating the manner of connection of the straps with the bridge bar of the buckle.

Referring more particularly to the accompanying drawing, in which like characters of reference refer to corresponding parts in the several views, the character 5 denotes the collar generally consisting of sides 6,

each of which has secured to its upper end flexible neck bands 7 and 8 respectively having formed therein spaced parallel rows of openings 9. 10 designates the neck pad embodying a flexible body 11, preferably constructed of leather or the like material and

concaved longitudinally and transversely of the upper and lower sides respectively, in order to adapt the pad to snugly engage over the neck of the animal, upon the connection of the collar to the neck of the animal. A retaining plate 12 of lesser length and width than the body portion and of a configuration to conform with the configuration of said body portion, is reposed upon the upper surface 13 thereof and fixedly secured thereto by rivets or the like fastening devices, denoted by the character 14. This retaining plate is stamped from a single blank of metal of the like material on which is reposed a transversely arranged 70 buckle 15. This buckle may be either in the form of a stamping, forging or casting and molded to conform with the contour or configuration of the retaining plate, whereby upon the fastening of the buckle to the 75 retaining plate by means of rivets 16, the reduced longitudinally alined ends 17 and the bulged ends 18 of the body 19 will fit flush therewith. The body denoted by the character 19 is stamped out to provide a 80 pair of openings 20 separated from one another through the medium of the bridge bar 21. Integrally connected with the buckle at points between the openings 20 and to opposite ends of the bridge bar 21, is a pair 85 of spaced perpendicularly arranged prongs 22 adapted to be projected through the openings 8 of the flexible neck band for connecting the neck band to the neck pad and in overlapped relation with respect to one another, and the accidental displacement of the neck band from the prongs is prevented by the curving of the prongs in a direction at right angles with the plane of the bridge bar. To hold the neck pad on the collar I 95 provide a strap 23 having one end secured to the collar and its other end passed through the apertures 20 and under the bridge bar. In this manner the pad is loosely and removably connected with the collar. The 100 pad is provided with straps 10' which are to be passed around the neck bands after the collar is placed in closed position.

From the foregoing description, taken in connection with the accompanying drawing, 105 the advantages of construction and the method of operation will be readily apparent to those skilled in the art to which the invention relates, and while I have described the principles of operation of the invention, 110

together with the device which I now consider to be the best embodiment thereof, I desire to have it understood that the device shown is merely illustrative and that such changes may be made when desired as are within the scope of the appended claims.

Having thus described the invention, what is claimed as new, is:—

1. In combination with a horse collar having flexible ends each provided with a series of spaced parallel openings, of a detachable neck pad, including a flexible body portion, a retaining plate secured to said body portion and concaved longitudinally and transversely of the upper and lower sides, a buckle arranged transversely of the retaining plate and secured at a point intermediate its ends, and provided with a pair of spaced openings, a strap secured to the collar and passing through said openings to hold the neck pad, a pair of perpendicular prongs formed integral with the buckle at a point intermediate said openings and adapted to be projected through the openings of the flexible ends for holding the latter in closed position.
2. In combination with a horse collar having flexible ends each provided with a series of spaced parallel openings, of a detachable neck pad, including a flexible body portion, a retaining plate secured to said body portion and concaved longitudinally and transversely of the upper and lower sides, a buckle arranged transversely of the retaining plate and secured at a point intermediate its ends, and provided with a pair of spaced openings, a strap secured to the collar and passing through said openings to hold the neck pad, a pair of perpendicular prongs formed integral with the buckle at a point intermediate said openings and adapted to be projected through the openings of the flexible ends for holding the latter in closed position, said prongs being curved to provide the same with upper hooked ends for holding the flexible ends of the collar in a locked closed position and straps carried by the pad and adapted to be placed around the neck bands after the same are placed over the prongs.

In testimony whereof I affix my signature.
JOHN C. NICHOLS.
